(57) **CLAIM**

The ornamental design for a cosmetics brush with rectangular ferrule, as shown and described.

DESCRIPTION

FIG. 1 is a perspective view of a first embodiment of a cosmetics brush with a rectangular ferrule;

FIG. 2 is a front elevation view of an embodiment of a cosmetics brush with a rectangular ferrule;

FIG. 3 is a rear elevation view of the embodiment of the cosmetics brush with a rectangular ferrule shown in FIG. 1; FIG. 4 is a left-side elevation view of the embodiment of the cosmetics brush with a rectangular ferrule shown in FIG. 1; FIG. 5 is a right-side elevation view of the embodiment of the cosmetics brush with a rectangular ferrule shown in FIG. 1;

FIG. 6 is a top plan view of the embodiment of the cosmetics brush with a rectangular ferrule shown in FIG. 1; and,

FIG. 7 is a bottom plan view of the embodiment of the cosmetics brush with a rectangular ferrule shown in FIG. 1. The brush head shown in broken lines in the drawings is environmental structure and forms no part of the claimed design.

1 Claim, 7 Drawing Sheets
